UNITED STATES PATENT OFFICE.

GOTTFRIED HEINRICH JACOB MAAS, OF BERLIN-STEGLITZ, GERMANY.

COMBINATION SOLE-PLATE AND RAILROAD-TIE.

1,078,297.

Specification of Letters Patent. Patented Nov. 11, 1913.

Application filed September 18, 1912. Serial No. 721,067.

To all whom it may concern:

Be it known that I, GOTTFRIED H. J. MAAS, a subject of the King of Prussia, German Emperor, and a resident of 88¹ Schlossstrasse, in the city of Berlin-Steglitz, Kingdom of Prussia and German Empire, have invented certain new and useful Improvements in Combination Sole-Plates and Railroad-Ties, of which the following is a specification.

The invention herein illustrated relates to an improvement of the fastening of the rails to the metallic cross-ties in order to preserve the ties longer and make them more durable. This improvement, applicable to all metallic cross-ties and shown with the tie, illustrated in the American Letters Patents of November 24th 1903 No. 744868 and of July 30th 1912 No. 1034389, is explained in the accompanying drawings, in which—

Figure 1 is a cross-section through an intermediate tie with view of the sole-plate and rail, in approximate measure 1:10; Fig. 2 is a cross-section through a joint-tie with a view of the sole-plate and rail; Figs. 3 and 4 are plans of Figs. 1 and 2; Fig. 5 is a longitudinal section through the tie and the sole-plate; Fig. 6 is a cross-section through an intermediate tie and the sole-plate on larger scale, approximately 1:3; Fig. 7 is a plan of a sole-plate for an intermediate tie; Fig. 8 is a cross-section of the sole-plate of Fig. 7; Fig. 9 is a cross-section through a joint tie and the sole-plate thereof; Fig. 10 is a longitudinal section through the intermediate or joint tie and the sole-plate thereof on the line *n-n* of Figs. 7 and 11; Fig. 11 is a plan of the sole-plate for the joint tie; Fig. 12 is a longitudinal section through the sole-plate of the joint tie on the line *m-m* of Fig. 11; Figs. 13, 14, 15 and 16 show less important small iron fittings for fastening the rail at the sole-plate.

For greater clearness' sake the fish-plates at the rail-joints are omitted in the drawings.

Experience with metallic cross-ties has proved, that these ties become prematurely useless only because fissures or slits break out near the holes of the tie, which are made for small iron fittings, to fasten the sole-plate and the rail, these holes weaken the carrying capacity of the tie especially at the point, where the rail is lying and where

the tie must have the greatest power of resistance. In order to remove this fault and to avoid the perforation of the tie at this spot, the tie is provided at the top with thicker side-ribs *r*, which have slots *s* cut out at the inner sides, in which the sole-plates enter by projecting keys *k*. The sole-plates are shoved in from the head end of the tie and secured against lifting-off by the slot and key. In order to avoid also a dislocating or moving of the sole-plates in the longitudinal direction of the tie, the sole-plates are arrested by gage-bars *b*, which are fixed by one bolt in the center of the tie. For the widening of the gage at curves, the outside gage-bar is prolonged as wanted. For fastening the rail to the sole-plate, a hook is provided at the outside of the sole-plate and at the inner side of the sole-plate a corresponding clip with headed bolt is seen, the head or double hook of which lies in a slot *S*, which is grooved in the under-side of the sole-plate, about 30 mm. thick, and which has only such breadth, that the hook of the headed bolt has a firm and strong seating place therein without being able to turn around. This headed bolt is to be stuck into the hole of the sole-plate, before shoving in the sole-plate in the slots *s* of the tie. The same is true of the headed bolt of the gage-bar. Consequently the tie has only one little hole in the center of its length for fastening the gage-bar at that point, where fissures cause no damage to the tie. By location of the holes of the ties according to the line of the track, the track itself may be adjusted simultaneously.

The ties as shown in the drawings may be rolled and finished and after that only need the cutting of the slots for the keys of the sole-plate from the head end of the tie to the seat of the sole-plate. The sole-plates are rolled crosswise, *i. e.* in the direction of the rail, and the slot *S* cut out in the under-side. In the sole-plate for the rail-joint, which bears the both rail ends of the rail-joint—compare above named Letters Patents—there are to be cut two slots *S* in the underside, and in the upperside the recess for the taking-up or facing rail end. The sole-plates can also be cast without additional work. The gage-bars are to be made of flat bar iron.

What I claim as my invention is:
Combination of the sole plate with the

railroad tie, the tie having an imperforate top under and near the seat of the sole plate and ribs with slots, the sole plate having keys at the outside edges; the said slots and 5 keys making possible the connection of the sole plate with the tie and permitting the elimination of holes in the tie and of small iron fittings.

In witness whereof I have hereunto signed my name in presence of two witnesses.
Berlin-Steglitz, September 7th 1912.

GOTTFRIED HEINRICH JACOB MAAS.
